(57) **CLAIM**

I claim the ornamental design for a dual beam aiming laser, substantially as shown and described.

DESCRIPTION

FIG. 1 is a top front right perspective view of a dual beam aiming laser;

FIG. 2 is a bottom rear left perspective view of a dual beam aiming laser;

FIG. 3 is a front elevational view of a dual beam aiming laser;

FIG. 4 is a top plan view of a dual beam aiming laser;

FIG. 5 is a rear elevational view of a dual beam aiming laser;

FIG. 6 is a bottom plan view of a dual beam aiming laser;

FIG. 7 is a left side elevational view of a dual beam aiming laser; and,

FIG. 8 is a right side elevational view of a dual beam aiming laser.

Dashed lines represent unclaimed subject matter and form no part of the claimed design.
